ALARM AND ANNUNCIATOR DEVICE

Eric D. Smith, Chicago, Ill.

Application August 17, 1950, Serial No. 180,049

12 Claims. (Cl. 340—213)

1

This invention relates to annunciators or alarm devices, particularly such as are adapted for use in engine rooms, power plants, industrial plants, and the like, for giving a signal of the existence of an abnormal condition at a specific place or machine, or part of a machine.

In accordance with the principles of the present invention a number of alarms or annunciator devices are connected each to one machine, or one part of a machine, the annunciators being all mounted adjacent to one another on a switchboard or the like. When an abnormal condition occurs on any of the machines or places that are to be protected a light operates on the particular annunciator, and an audible alarm is given. The alarm calls the attendant's attention to the annunciators, and a light on the particular annunciator involved indicates the type of fault or other condition involved, and the location thereof.

The present invention is particularly adapted for use where certainty of operation is of utmost importance and where signals must indicate not only momentary alarms which can be reset at once, but also must indicate abnormal conditions which may remain for some time, and once such abnormal conditions have occurred the annunciator must indicate the continuance of the abnormal condition, and when the abnormal condition has been cleared the annunciator must affirmatively indicate that fact.

It is a further object of the present invention to provide an annunciator which includes a lamp which is mounted on or part of a movable pointer. The separate positions of the pointer indicate the respective conditions of the circuit associated with that annunciator and the lighted lamp on the pointer serves to attract the operator's attention to the particular annunciator wherein the pointer is moved to the off-normal position. In order to accomplish the above results each particular annunciator of the present invention has a number of separate positions which, for the purpose of description, will be called the "normal," "alarm," "trouble," and "clear" positions.

It is a further object of the present invention to provide an annunciator wherein the pointer constitutes a manually reset key which also operates a spring loading device that controls the automatic operation of the annunciator so that the automatic operation can be controlled by a solenoid operated trip latch which requires very little power.

Since the pointer is also the reset key each alarm device or annunciator is a complete unit and requires no additional bell reset, drop reset,

2

relays or housing, and can therefore be mounted singly or in any desired number or arrangement.

It is a further object of the present invention to provide an annunciator wherein the pointer or reset key is so constructed that it can be plugged into or pulled out of the rest of the structure as may be necessary in the event of lamp failure or if a change of color is desired.

It is a still further object of the present invention to provide an alarm device so constructed that it gives one audible signal when it is energized to its alarm position and a different audible signal when it is energized to move from a "trouble" position to a "clear" position.

In accordance with the principles of the present invention the visual signal or light is "off" when the annunciator is in its "normal" position, and the light is on when the annunciator is in any of its off-normal positions. If a fault is one which may remain for some time the operator then moves the pointer, which includes the lamp, to the "trouble" position. In this position the audible signal is discontinued but the visual signal is continued, thus indicating the existence of a "trouble" condition which must be cleared. If that trouble condition is then cleared, after the visual signal of the annunciator has been moved from the "alarm" position to the "trouble" position, the clearance of the trouble then causes the alarm indicator to move to a fourth position, where it remains lighted indicating a "clear" condition, and a different audible signal is given to call attention to the fact that the trouble which previously existed has been cleared. The annunciator can then be moved from the "clear" position back to the "normal" position.

The attainment of the above and further objects of the present invention will be apparent from the following specification taken in conjunction with the accompanying drawing forming a part thereof.

In the drawing:

Figure 1 is a diagrammatic view of the annunciator, showing the circuit connections when the parts are in their "normal" positions.

Figures 2, 3 and 4 are diagrammatic views corresponding to Figure 1 and showing the annunciator in the "alarm," "trouble" and "clear" positions, respectively;

Figures 5, 6, 7 and 8 are diagrammatic views of the latching and spring arrangements when the parts are in their "normal," "alarm," "trouble" and "clear" positions, respectively;

Figure 9 is a longitudinal view of the communicator shaft and key, in partial section;

Figures 10, 11 and 12 are sections taken on Figure 9 along the lines 10-10, 11-11, and 12-12, respectively, and looking in the direction of the arrows;

Figure 13 is a front view of the pointer; and

Figure 14 is a fragmentary view showing an alternate location of the control relay.

Reference may now be had more particularly to the drawings wherein like reference numerals designate like parts throughout.

The annunciator of the present invention, indicated by the reference character "A," is adapted to be electrically connected to a power source, indicated by power leads 1-1', which may be any alternating or direct commercial current source. Figure 1 shows, schematically, the electric diagram and the relative positions of the parts when a remote control alarm contact 2 is open and the device is latched in its "normal" position. The remote alarm contact 2 is an electric contact located at the place where trouble is to be detected and is arranged to be actuated whenever trouble occurs. In the present instance it is shown as a normally open contact arranged to be closed when trouble occurs. It can equally well be a normally closed contact arranged to be opened when trouble occurs, in which event an abnormal condition would be manifested by the opening of a normally closed circuit, as will be apparent as this description proceeds. The remote alarm contact 2 controls the circuit to the winding of an electromagnetic coil 4 of the relay type, which in turn controls an armature 6. When the coil 4 is not energized the armature 6 is held in the position shown in Figure 1, which is the position away from the coil. It is held in that position by a spring or by gravity as is usual in the relay art. The armature 6 is here shown as pivoted at 7 and carrying at one end thereof an armature latch 8 which, in the position shown in Figure 1, engages a commutator shaft latch pin 10 that is rigid with and extends outwardly from a rotatable commutator shaft 11. The shaft is arranged to be turned in one direction manually by a pointer or key 12, shown more particularly in Figure 9, against the action of one or more springs which serve to restore the shaft under control of the armature 6 acting through its latch 8 and another latch to be later described. It is sufficient here to state that the pointer or key 12 is located at the front of the annunciator and carries a visible signal in the form of an electric lamp 13 which may be of the glow discharge type or any other type as desired. It is sufficient here to state that when the parts are in the position illustrated in Figure 1, which is the "normal" position, the shaft is spring biased to urge it to turn to the "alarm" position of Figure 2, but is held by the armature latch 8 against turning to that position. The key 12 is releasably secured to the shaft 11 to turn therewith and is adapted to turn the shaft 11 under control of the armature 6. The key 12 includes a tip contact 14 and a ring contact 18 that are adapted to engage commutator rings 16 and 20, respectively, on the commutator shaft 11. The tip 14 is connected to one side of the lamp by a conductor 15 while the other side of the lamp 13 is permanently connected through a resistor 17 to the ring 18. The commutator ring 16 which is mounted on the commutator shaft 11 includes a flat portion 19 that is in contact with the tip 14 in all rotatable positions of the shaft 11, and a circular portion 21 that is adapted to engage

a stationary brush or contact 22 in certain positions of the commutator shaft. The commutator ring 20 includes a flat portion 23 that is always in engagement with the ring 18 and arcuate portions 24 and 25 that are adapted to engage brushes or contacts 26, 27 and 28 in various positions of the shaft 11. The contacts 22 and 26 are connected to line conductors 1' and 1, respectively, whereas the contacts 27 and 28 are connected to two different audible alarms 29 and 30 which in turn are connected to the line 1'. The audible alarms 29 and 30 are designed so that they give distinctly different sounds. For instance, one may be a bell and the other may be a buzzer. When conditions are "normal" and the parts are in the positions illustrated in Figure 1 the circuits for the lamp 13 and for the alarms 29 and 30 are open.

A description will now be given of the operation of the device upon the occurrence of an abnormal condition which results in the closure of the switch contacts 2. This causes energization of the winding 4 and consequent attraction of the armature 6. The armature 6 pivots about the pivot 7 and withdraws the latch 8 from the path of the latch pin 10. This allows the rotatable commutator shaft 11 to turn, under the action of its spring to be hereafter described, to the position illustrated in Figure 2. In this position a circuit is established for the lamp 13 by the engagement of the commutator 16 with the contact 22 and engagement of the commutator 20 with the contact 26. At the same time the commutator portion 25 engages the contact 28 and thus completes a circuit for the audible alarm 30. At this time the contact 27 is free of the commutator ring 24 so that no circuit is established to the audible alarm 29. The audible alarm 30 calls the operator's attention to the annunciator and when there are many side by side annunciator devices on the switchboard the lighted condition of the particular lamp 13 informs the operator which annunciator has operated, and the position of the pointer key 12 also indicates which circuit is in trouble.

If the alarm is a momentary type alarm the contact 2 opens at once and deenergizes the coil 4 allowing the armature 6 to return to the position of Figure 1. The operator can then manually turn the key 12 back to "normal," thus loading the return spring and latch in the "normal" position as shown in Figure 1. If the alarm is a maintained type alarm the contact 2 remains closed and the coil 4 remains energized so that the armature 6 remains pulled towards the coil 4, as shown in Figures 2 and 3. The operator cannot then turn the key back to the "normal" position and leave it there because as soon as the operator releases the key 12 there is immediate restoration of the shaft 11 to the alarm position of Figure 2. The operator can, however, turn the key 12 from the "alarm" position onward to the "trouble" position indicated in Figure 3, where the latch pin 10 engages an armature latch 31 at that end of the armature 6 opposite where the latch 8 is located. This latches the shaft in the "trouble" position. At this time the contacts 27 and 28 are free and clear of the commutator ring 20 so that the circuits for both audible alarms 29 and 30 are open. The lamp 13 is now in its "trouble" position and remains lighted by reason of the fact that the contact 28 is in engagement with the portion 24 of the commutator ring 20 which completes an operating circuit for the lamp 13. The rotatable com-

mutator shaft 11 is held in the "trouble" position by the latch 31 so long as the armature 6 remains attracted to the core of the relay by the energization of the winding 4. The operator can now tell both by the position of the key 12 and the lighted lamp that a "maintained" trouble exists on a particular circuit.

When the trouble has cleared on the particular circuit involved the contact 2 opens, thus deenergizing the winding 2 and permitting the armature 6 to restore to its normal position. This moves the latch 31 free of the latch pin 10 on the armature shaft 11 and the shaft therefore rotates under its spring loading from the position illustrated in Figure 3 to the position illustrated in Figure 4. In this position the circuit for the lamp 13 remains closed because of engagement of the contact 26 with the portion 24 of the commutator ring 20. At this time also the portion 25 of the commutator ring 20 engages the contact 27 and establishes a circuit for the audible alarm 29. This alarm, being different in sound from that of the alarm 30, informs the operator that the previously existing trouble has been cleared. The lighted condition of the signal lamp and the position of the key 12 indicate the particular location where the trouble has been cleared. The operator can then turn the key 12 from the "clear" position of Figure 4 to the "normal" position of Figure 1 to restore normal conditions of the annunciator "A." When the operator has turned the key 12 and therefore the shaft 11 to the "normal" position, while the armature 6 and its latch are in their deenergized position as illustrated in Figures 1 or 4, the latch pin 10 rides over the curved back of the latch 8 and then engages the latch which thereupon acts on the pin to hold the shaft 11 against return rotation by its loading spring.

Reference may now be had more particularly to Figures 5 through 9 which show the mechanical arrangement for biasing and actuating the commutator shaft 11. The commutator shaft latch pin 10 is rigidly secured to the shaft and has a projection 36 against which an end of a coiled spring 37 bears. In the "normal" position one end of the spring bears against the projection 36 and the other end bears against a stop pin 32 that is carried by a stationary plate 38, said pin projecting at right angles to the plate and extending through an arcuate slot 39 in the plate, in which slot it is slidable, being held in its adjusted position by a spring washer 40 that is pressed against the bearing plate 38 by a pair of lock nuts 41-41 on the pin 32. Two pin positioning cams 43-44 are mounted on the shaft 11 to rotate therewith. These cams engage the stop pin 32 and move it from one position to the other in the slot 39, depending upon the position and movement of the shaft 11, by the manual turning of the key 12.

When the annunciator is in the normal position the spring urges the shaft 11 in a direction counter-clockwise as seen in Figure 5, which motion of the shaft is prevented by the latch 8. When the latch 8 is retracted by energization of the coil 4 and consequent movement of the armature 6 (Fig. 1) the shaft 11 moves to the "alarm" position illustrated in Figure 6. In this movement the positioning cam 43 moves away from the stop pin 32 and the spring arm 33 moves up to engagement with the stop pin 32. This limits the extent of rotation of the shaft 11 to the "alarm" position illustrated in Figure 6.

The operator can then turn the key in a direc-

tion counter-clockwise, as seen in Figure 6, from the position of Figure 6 towards the position of Figure 7. In the movement of the shaft 11 from the position of Figure 6 towards the position of Figure 7 the projecting pin 36 first engages the spring end 33 and tensions the spring. At this time the end 33 of the spring remains in contact with the stop pin 32. Loading of the spring continues until the positioning cam 44 engages the stop pin 32. Therefore continued turning of the shaft causes the positioning cam 44 to move the stop pin 32 in the slot 39, thus causing the two ends 33-35 of the spring both to move together, the end 33 of the spring following the stop pin 32. This condition continues until the "trouble" position of Figure 7 is reached at which time the stop pin 10 rides over the latch 31. If the "trouble" is a maintained trouble the latch 31 is in its latching position so that when the shaft reaches the position of Figure 7 and the operator releases the key 12, the pin 10 is latched by the latch 31. At this time the spring end 33 is in engagement with the projection 36 on the pin 10 and urges the shaft 11 in a direction clockwise as seen in Figure 7, towards the position of Figure 8, being kept from moving to that position by the latch 31. When the trouble clears and the coil 2 is deenergized the latch 38 swings out of position and thus permits the spring end 33 to rotate the shaft 11 until the spring end comes in contact with the stop pin 32. This is the "clear" position illustrated in Figures 4 and 8. The operator can then turn the shaft 11 in a direction clockwise as seen in Figure 8, back to the "normal" position by turning of the key 12. When the shaft is turned clockwise from the position of Figure 8 to the position of Figure 5 the stop pin 32 first holds the spring end 35 while the projection 36 moves with the spring end 33 to load the spring. This continues until the positioning cam 43 engages the stop pin 32. Thereafter continued turning of the shaft causes the stop pin 32 to move with the projection 36, maintaining the loaded condition of the spring, until the stop pin 10 rides under and is engaged by the latch 8, at which time the shaft 11 is in its "normal" position and a release of the key 12 leaves the shaft 11 latched in the "normal" position.

Reference may now be had more particularly to Figures 9, 10, 11 and 12 which show the construction of the key 12 and the rotatable commutator shaft. The key fits into the hollow end of the shaft 11 and is held there by friction and may be inserted or withdrawn at will. The commutator shaft 11 comprises a cylindrical insulating stud 50 which extends through a circular hole in a plate 51 on which the cams 43-44 are formed. The plate 51 is secured to a plastic tubular sleeve 52 in any desired manner as, for instance, by a set screw 54. The cylindrical stud 50 fits into the sleeve 52 and is secured thereto as by a set screw 56. The stud 50, plate 51, and sleeve 52 thus constitute one unit which is the commutator shaft 11. The end of the stud within the sleeve has a longitudinal key slot 57 therein for receiving a flat shank which constitutes the tip of the key 12, as will be hereinafter explained. The commutator rings 16 and 20 are mounted on the plastic tubular sleeve 52 and to that effect the sleeve is slotted, as indicated at 58 and 59.

The key 12 comprises a molded body of insulation in which is embedded the lamp 13, the resistor 17, the tip terminal 14 and the ring 18. The tip terminal 14 comprises a copper rod 60 one end of which is flattened, as indicated at 62,

to constitute a key that fits into the slot 57 of the stud 50. A body of plastic 65 is molded around the rod, the lamp 13, the resistor 17 and also holds the ring 18. One terminal of the lamp is connected directly to the rod 60 and the opposite terminal of the lamp connects through the resistors 17, from which a copper conductor extends from the other terminal of the resistor to the ring 18, that conductor also being embedded in the plastic 65. The plastic 65 is preferably clear transparent plastic, although it is within the purview of this invention to use a colored transparent plastic. The key assembly may be inserted into and removed from the annunciator by a simple plug in or pull out action. When that is done the tip portion 62 engages the flat part 19 of the commutator 16 and flexes it outwardly a very slight amount. The flat key part 62 has a pair of slight notches therein so that the flat portion 19 of the commutator spring 16 engages one of those notches and resiliently holds the plug in the sleeve 52. At the same time the flattened end 62 enters the key slot 57 in the stud 50 so that by turning of the key the operator can turn the shaft 11 which includes the stud 50 and the plate 51 and the tubular sleeve 52.

In some annunciators it is desirable to have the annunciator indicate normal conditions upon the existence of a closed circuit and indicate abnormal conditions when that circuit is open. This result can be obtained with the annunciator of the present invention by shifting the position of the relay 4, as indicated in Figure 14. When this is done the relay is connected in circuit with normal closed switch contacts 2' that are located on the machine or part of the machine to be protected. The armature 6 of the relay is therefore normally attracted by the magnetic action of the winding 4 in a closed circuit. When the winding 4 is open circuited, as by opening of the switch 2', the armature 6 is moved to its alternative position, namely, the position of Figure 2, by a spring or the like.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. An electric alarm device comprising a spring loaded rotatable member, latch means for latching said member in either of two positions, electromagnetic latch means, means effective upon actuation of the latch means for stopping restoration of the member under its spring loading in either of two different positions depending upon the position in which the member had last been latched, and a removable key fitting said rotatable member for turning it and being also turned by said member so that the position of the key indicates the position of the rotatable member.

2. An electric alarm device comprising a spring loaded rotatable member, latch means for latching said member in either of two positions, electromagnetic latch means, means effective upon actuation of the latch means for stopping restoration of the member under its spring loading in either of two different positions depending upon the position in which the member had last been latched, a removable key fitting said rotatable member for turning it and being also turned by

5 said member so that the position of the key indicates the position of the rotatable member, an electric signal light carried by said key, and contact means controlled by the turning of said member for controlling said signal light.

3. In an electric alarm device a rotatable member having two stop positions and manually movable from one stop position to the other, spring means and means for loading the spring means upon rotation of the member in one direction from one stop position and in the other direction from the other stop position, means for latching the member in positions reached upon rotation in one direction from one stop position and in the opposite direction from the opposite stop position, and electromagnetic means for releasing the latch means whereby the rotatable spring loaded member returns to the corresponding stop position.

4. In an electric alarm device a rotatable member having two stop positions and manually movable from one stop position to the other, spring means and means for loading the spring means upon rotation of the member in one direction from one stop position and in the other direction from the other stop position, means for latching the member in positions reached upon rotation in one direction from one stop position and in the opposite direction from the opposite stop position, electromagnetic means for releasing the latch means whereby the rotatable spring loaded member returns to the corresponding stop position, and plug-in key means for rotating the rotatable member from one stop position to the other and from either stop position to either spring loaded latched position, said key means being insertable into said rotatable member and being rotatable thereby so that the position of the key means indicates the position of the rotatable member.

5. In an electric alarm device a rotatable member having two stop positions and manually movable from one stop position to the other, spring means and means for loading the spring means upon rotation of the member in one direction from one stop position and in the other direction from the other stop position, means for latching the member in positions reached upon rotation in one direction from one stop position and in the opposite direction from the opposite stop position, electromagnetic means for releasing the latch means whereby the rotatable spring loaded member returns to the corresponding stop position, plug-in key means for rotating the rotatable member from one stop position to the other and from either stop position to either spring loaded latched position, said key means being insertable into said rotatable member and being rotatable thereby so that the position of the key means indicates the position of the rotatable member, and signal circuits controlled from different positions of the member.

6. In an electric alarm device a rotatable member having two stop positions and manually movable from one stop position to the other, spring means and means for loading the spring means upon rotation of the member in one direction from one stop position and in the other direction from the other stop position, means for latching the member in positions reached upon rotation in one direction from one stop position and in the opposite direction from the opposite stop position, electromagnetic means for releasing the latch means whereby the rotatable spring loaded member returns to the corresponding stop posi-

tion, and signal circuits controlled from different positions of the member.

7. In combination with a number of similar electric alarm devices each including a rotatable member having a stop position, spring means and means for loading the spring means upon rotation of the member from the stop position, means for latching the member in its spring loaded position, electromagnetic means for releasing the latch means whereby the rotatable spring loaded member returns to the stop position, plug-in key means for rotating the rotatable member from the stop position to the spring loaded latched position, said key means being insertable into said rotatable member and being rotatable thereby so that the position of the key means indicates the position of the rotatable member; and signal circuits common to all of said devices and controlled by rotation of the member of any of said devices, whereby the operation of a signal circuit indicates the operation of an alarm device and the position of the rotatable member on one of the devices indicates which device has operated.

8. In an electric alarm device a rotatable member having a stop position, spring means and means for loading the spring means upon rotation of the member from the stop position, means for latching the member in its spring loaded position, electromagnetic means for releasing the latch means whereby the rotatable spring loaded member returns to the stop position, plug-in key means for rotating the rotatable member from the stop position to the spring loaded latched position, said key means being insertable into said rotatable member and being rotatable thereby so that the position of the key means indicates the position of the rotatable member, signal circuits controlled by rotation of the member, and a signal light mounted on the key and connected in one of the circuits.

9. In an electric alarm device a rotatable member having two stop positions and manually movable from one stop position to the other, spring means and means for loading the spring means upon rotation of the member from either stop position, means for latching the member in different positions reached upon rotation from either stop position, and electromagnetic means for releasing the latch means whereby the rotatable spring loaded member returns to the corresponding stop position.

10. In an electric alarm device a rotatable member having two stop positions and manually movable from one stop position to the other, spring means and means for loading the spring means upon rotation of the member from either stop position, means for latching the member in different positions reached upon rotation from

either stop position, electromagnetic means for releasing the latch means whereby the rotatable spring loaded member returns to the corresponding stop position, and plug-in key means for rotating the rotatable member from one stop position to the other and from either stop position to either spring loaded latched position, said key means being insertable into said rotatable member and being rotatable thereby so that the position of the key means indicates the position of the rotatable member.

11. In an electric alarm device a rotatable member having two stop positions and manually movable from one stop position to the other, spring means and means for loading the spring means upon rotation of the member from either stop position, means for latching the member in different positions reached upon rotation from either stop position, electromagnetic means for releasing the latch means whereby the rotatable spring loaded member returns to the corresponding stop position, and signal circuits controlled from different positions of the member.

12. In an electric alarm device a rotatable member having two stop positions and manually movable from one stop position to the other, spring means and means for loading the spring means upon rotation of the member from either stop position, means for latching the member in different positions reached upon rotation from either stop position, electromagnetic means for releasing the latch means whereby the rotatable spring loaded member returns to the corresponding stop position, plug-in key means for rotating the rotatable member from one stop position to the other and from either stop position to either spring loaded latched position, said key means being insertable into said rotatable member and being rotatable thereby so that the position of the key means indicates the position of the rotatable member, and signal circuits controlled from different positions of the member.

ERIC D. SMITH.
